Primary Examiner — Susan Bennett Hattan(74) *Attorney, Agent, or Firm* — Banner & Witcoff, Ltd.(57) **CLAIM**

The ornamental design for a lid for a container, as shown and described.

DESCRIPTION

FIG. 1 is a magnified, fragmentary, front, top perspective view of a container showing our new design for a lid for a container;

FIG. 2 is a front, top perspective view thereof;

FIG. 3 is a top view thereof; and,

FIG. 4 is a right side view thereof, with the left side, front, and rear views appearing identical thereto.

The even-length broken lines represent claimed perforations on the lid for the container. The uneven-length broken lines showing the remainder of the lid and container are for illustrative purposes only and form no part of the claimed design.
